UNITED STATES PATENT OFFICE

96,528

DESIGN FOR A COASTER

Katherine Brown, Paris, Tenn.

Application June 6, 1935, Serial No. 57,174

Term of patent 3½ years

To all whom it may concern:

Be it known that I, Katherine Brown, a citizen of the United States, residing at Paris, in the county of Henry and State of Tennessee, have invented a new, original, and ornamental Design for a Coaster, of which the following is a specification, reference being had to the accompanying drawing, forming part thereof.

I claim:

The ornamental design for a coaster, as shown.

KATHERINE BROWN.
